UNITED STATES PATENT OFFICE

ROY J. WENSLEY, OF EDGEWOOD, PENNSYLVANIA, ASSIGNOR TO WESTINGHOUSE ELECTRIC & MANUFACTURING COMPANY, A CORPORATION OF PENNSYLVANIA

CIRCUIT-BREAKER-TRIPPING SYSTEM

Application filed May 27, 1932. Serial No. 366,310.

My invention pertains to protective systems for electric circuits and, particularly, to sectionalizing systems for direct-current railway-distribution circuits.

It is the principal object of my invention to provide a high-speed sectionalizing circuit breaker with means for controlling its operation in accordance with the impedance of the circuit to be protected.

It is a further object of my invention to improve upon high-speed circuit breakers, as now applied to direct-current circuits, by the incorporation therewith of an impedance element similar to that of the well known impedance relay which has been developed for, and applied to, the protection of alternating-current circuits.

The structure of the so-called high-speed circuit breaker is now well known as consisting of a contact mechanism, a holding magnet for maintaining the mechanism in closed position and a flux-shifting coil, usually of one turn, called a "bucking bar", for shifting the flux traversing the magnetic circuit of the holding magnet, to permit the circuit breaker to be released so that it will open its contacts, upon the occurrence of an overload on the circuit to which it is connected. While this structure is a great improvement over those previously known, it has one disadvantage, namely, that it does not distinguish between a fault condition and a heavy-load condition.

It is another object of my invention to provide the usual high-speed circuit breaker with means for detecting the difference between fault and heavy-load conditions.

In accordance with my invention, I employ, in addition to the bucking bar, a second flux-shifting winding which I connect, in series with a condenser, across the circuit to be protected. Under normal conditions, the second flux-shifting winding is deenergized, since direct current will not traverse the condenser. Upon the occurrence of a fault, however, the voltage of the circuit to be protected will naturally be so lowered that a transient current traverses the condenser and the latter discharges through the flux-

shifting winding to cause the tripping of the circuit breaker.

For a more complete understanding of my invention, reference is made to the accompanying drawing, the single figure of which is a diagrammatic illustration of the system and apparatus of my invention.

Referring particularly to the drawing, a source of direct-current energy, such as a substation bus, is indicated at 10. A distribution circuit, such as a feeder 11, is adapted to be connected to the bus 10 through the contact member of a circuit interrupter indicated generally at 12. The circuit interrupter 12 is of the type which is maintained closed by a holding electromagnet indicated at 13. A spring 14, or other equivalent means, is provided to effect the tripping of the circuit breaker 12 when the holding magnet is rendered ineffective.

The holding magnet 13 consists of a core 15 having pole pieces 16 and 17. An armature member 18 is adapted to cooperate with the pole pieces 16 to maintain the circuit breaker closed so long as flux traverses the pole pieces 16 and armature member 18. The holding magnet is normally excited by means of a holding coil 19 which may be connected across the circuit 11 or to a separate source of current. The bucking bar is indicated at 20 and, in the usual manner, is arranged to provide such magnetomotive force, when traversed by an electric current, as to shift the flux from the pole pieces 16 and armature 18 to the pole pieces 17 and the air-gap therebetween. The bucking bar is so connected across a reactor 21 in the circuit 11 as to be energized in accordance with the rate of change of the current traversing the feeder 11.

In addition to the bucking bar 20, I provide also a second flux-shifting winding 22 which may, for convenience, be wound on the pole pieces 17. The winding 22 is connected across the circuit 11 in series with a condenser 23. Under normal conditions, of course, no current will traverse the condenser 23 but it will remain charged so long as normal voltage exists across the circuit 11. Should the voltage fall below its normal

value, the condenser will tend to discharge itself through the flux-shifting winding 22. I employ this principle to produce a tripping impulse for the circuit breaker 12 which shall be responsive, in part, to the drop in the voltage of the circuit 11 which is, of course, an indication of the severity of the fault which has occurred.

If a plurality of circuit breakers provided with the operating mechanism shown and described herein, are connected in series in a distribution circuit, it is obvious that the constants of the various elements of the combination may be so designed that the desired operating characteristics may be obtained. If, for example, the reactor 21 is designed to shunt a large portion of the fault current from the bucking bar 20, so that the shifting of the flux of the holding magnet is accomplished largely by the coil 22, the circuit breaker located nearest to the fault will be tripped first because its flux-shifting winding 22 is affected by the drop in circuit voltage to a greater degree than those of more distant breakers. By this means, it is possible to cause the isolation of a faulty section without interrupting service on remaining sections of the system.

Although I have shown and described but a single modification of my invention, I do not intend to be limited thereto, since changes and modifications will be apparent to those skilled in the art, and the appended claims are relied upon to define the scope of my invention.

I claim as my invention:

1. The combination with an electric circuit, a reactor and a condenser associated therewith, a circuit interrupter in said circuit biased to the open position, of a normally excited electromagnet for holding said interrupter in closed position, means for displacing the normal flux of said magnet comprising a bucking winding adapted to be connected across said reactor and a bucking winding adapted to be connected across said circuit in series with said condenser.

2. In a system for operating a circuit interrupter biased to the open position and adapted to be maintained closed by a normally energized electromagnet, a reactor and a condenser associated with the circuit controlled by said interrupter, windings for shifting the flux traversing said electromagnet, one of said windings being connected across said reactor and another being connected across said circuit in series with said condenser.

3. A circuit-breaker-operating mechanism comprising a normally energized holding electromagnet having flux-shifting windings adapted to be connected, respectively, across a reactor in the circuit controlled by the circuit breaker and across said circuit in series with a condenser.

4. A protective system for an electric circuit including an interrupter, a holding electromagnet for maintaining the interrupter closed, flux-shifting coils on said electromagnet, and means for energizing said coils, respectively, in accordance with the rate of change of the current traversing said circuit and the decrease in the voltage thereof. 70

5. In combination, a circuit, an interrupter therein, an electromagnet for maintaining said interrupter closed, means for modifying the flux of said magnet to permit the interrupter to open, said means comprising flux-shifting windings responsive to the rate of change of the current traversing said circuit and to the voltage thereacross. 75

6. A device for operating a circuit breaker including an electromagnet for maintaining the circuit breaker closed and means responsive to the rate of change of the current traversing said circuit and to the voltage thereacross for rendering said electromagnet ineffective. 85

7. A device for operating a circuit breaker including means actuated by a winding connected across a reactor in the circuit to be interrupted, and a winding in series with a condenser connected across said circuit. 90

8. In a circuit breaker, means tending to open said breaker, means for holding said breaker closed, means for releasing said holding means including a winding connected across a reactor in the circuit to be interrupted, and a winding in series with a condenser connected across said circuit. 95

9. In a circuit interrupter, separable contact means, means biasing said separable contact means to separated position, a magnetic core member having a normally energized winding for holding said contact means closed against said biasing means, a flux shifting winding connected to the circuit controlled by said circuit interrupter for releasing said separable contact means in response to predetermined current conditions in said circuit, said core member having thereon an additional winding which is normally deenergized and which causes the release of said separable contact means when energized, and means for energizing said normally deenergized winding. 100

10. In a circuit interrupter, separable contact means, means biasing said separable contact means to separated position, an armature connected to said separable contact means and a magnetic core member for attracting said armature and holding said separable contact means closed against said biasing means, said core member having a normally energized winding for energizing said core member to hold said armature, said core member having pole pieces providing parallel magnetic flux paths one of which is completed by said armature, a conductor positioned between said parallel flux paths for 110

shifting the flux from said armature to the other flux path upon the occurrence of a pre-determined current condition, said core member having an additional winding thereon which is normally deenergized and which causes the release of said separable contact means when energized, and means for energizing said normally deenergized winding.

11. In a circuit interrupter, separable contact means, means biasing said separable contact means to separated position, an armature connected to said separable contact means and a magnetic core member for attracting said armature and holding said separable contact means closed against said biasing means, said core member having a normally energized winding for energizing said core member to hold said armature, said core member having pole pieces providing parallel magnetic flux paths one of which is completed by said armature, a conductor positioned between said parallel flux paths for shifting the flux from said armature to the other flux path upon the occurrence of a pre-determined current condition in the circuit through the circuit interrupter, said core member having an additional winding thereon which is normally deenergized and which causes the release of said separable contact means when energized, and means for energizing said normally deenergized winding upon the occurrence of an electrical condition in the circuit different from that which causes the flux to be shifted from the armature to the other flux path.

In testimony whereof, I have hereunto subscribed my name this 17th day of May, 1929.

ROY J. WENSLEY.
